11 Claims. (Cl. 221—60)

This invention relates to measuring valves for collapsible tubes and has for its principal object to provide an improved measuring valve for use with these tubes.

5 The present invention consists in the provision of a measuring valve for use with collapsible tubes wherein the automatic advancement of the valve under the influence of the pressure exerted on the tube ensures the closure at the desired 10 moment of the evacuating orifice or orifices.

A convenient form of the invention will hereinafter be described, together with a modification thereof, which is given only by way of example, with reference to the accompanying drawing 15 in which:—

Fig. 1 shows in axial longitudinal section one form of the invention comprising a valve and cap in a tube nozzle;

Fig. 2 is an axial longitudinal section view 20 through the valve alone;

Fig. 3 is an axial longitudinal section through the cap alone;

Fig. 4 is an axial longitudinal section of another form of the invention.

25 Hitherto collapsible tubes generally have been closed by a screw-threaded stopper, the material contained in the tube being expelled by simple pressure on the tube after the stopper has been unscrewed. Under these conditions, an indefinite quantity of material was expelled at each 30 pressure, any prolonged pressure causing the contents of the tube to be expelled without stopping.

The invention has several advantages. On 35 the one hand, from a constructional point of view, tubes having a smooth nozzle are easy to manufacture and it is also easier to put the screw-thread on the valve than on the tube. The thread is the only part which is delicate to manufacture. It has, moreover, the advantage in certain lead tubes plated with tin that the lead is not exposed when making the screw-thread. Another advantage lies in the fact that the placing in position of the cap effects the closing of the 40 valve, so that when the cap is unscrewed the valve is still closed and can only be opened by manipulation by the user. Therefore there is no danger, as there is frequently with tubes hitherto in use, of the material being expelled from 45 the tube when the cap is unscrewed.

From the arrangement shown in Figures 1 to 3, it will be seen that there is a smooth nozzle 2 of a collapsible tube 1, a valve with a tubular stem 4 of which the flat part 5 is adapted to be 5 applied to the internal upper surface of the tube

1. Perforations 7 put into communication the hole 6 in the tubular stem with the interior of the tube when the valve is open. This tubular stem is guided in any suitable manner in the nozzle 2, in such a way that it cannot turn in the nozzle and is only permitted a longitudinal movement. The guide in question may be constituted for example by a longitudinal grooving or milling provided on a slightly thickened part of the stem of the valve. This grooving or milling wears a passage in the lead of the nozzle sufficient to ensure guidance. The plate of the valve may be provided with a groove 11, which permits the maintenance of the valve in position, by means of an appropriate tool correctly centered at the time of its first being placed in position.

At its upper part the tubular stem 4 of the valve has a screw-thread 12 adapted to pass into the nozzle 2. This screw-thread 12 is adapted to co-operate with an internal screw-thread 13 of the cap 3. This cap also has a conical portion 14 adapted to co-operate with the exterior conicity of the nozzle 2. Tightness of the closure is ensured on the one hand by the disc 15 of cork or other similar material lodged in the cap and supported on the edge of the tubular stem 4 and on the other hand by the co-operation of the conical portions 14 of the cap with the external conicity of the nozzle 2, and finally, in addition, by the bearing of the upper part of the flat part 5 against the interior of the upper part of the tube, this bearing being ensured by the pressure of the cap 3 which is supported on the nozzle 2.

35 The operation of the device is as follows:—

The cap is unscrewed and the tubular stem is thrust back toward the interior of the tube, for example by pressing the surface against an object, and pressure is applied to the tube. A predetermined quantity of the material will come out which corresponds to the stroke of the valve necessary for the perforations 3 to be reclosed. At the same time the screw-thread is re-projected outside the nozzle.

40 The method of construction of Figure 4 is very similar, but the cap 3^a is much smaller and simply bears on the edge of the nozzle 2, without having the supplementary closure assured in Figure 1 by conicity of the nozzle 2.

45 The operation is the same as in the preceding case. The flat part of the valve and the holes may, of course, be of any shape and size. The valve and its stem may be made of any suitable 50 55

material, for example, material known under the registered trade-mark as bakelite, or the like.

It will of course be understood that it is possible to regulate the quantity of material evacuated by modifying the evacuating orifices or by the effect on the speed of advancement of the valve. This speed is governed by varying the cross-section of the outlet nozzle and by modifying the surface of the head of the valve, or by 10 one or the other of these two means.

What I claim is:—

1. A collapsible tube having a nozzle, a valve 15 slideable in said nozzle and having a stem projecting from said nozzle, screw threads on said stem, means affording a passage for extrusion of the tube contents when said valve is pressed inwardly, and a cap which, when screwed on said stem prevents extrusion of the tube contents.

2. A collapsible tube having a nozzle which is 20 smooth both internally and externally, a valve slideable in said nozzle and having a stem projecting from said nozzle, screw threads on said stem, means affording a passage for extrusion of the tube contents when said valve is pressed inwardly, and a cap which, when screwed on said stem prevents extrusion of the tube contents.

3. A collapsible tube having a nozzle, a valve 30 slideable in said nozzle and having a stem projecting from said nozzle, said valve having a passage therethrough, screw threads on said stem, and a cap adapted to be screwed on said stem to engage said nozzle and prevent extrusion of the tube contents.

4. A collapsible tube having a nozzle which is 35 smooth internally and externally, a valve slideable in said nozzle and having a stem projecting from said nozzle, said valve having a passage therethrough, screw threads on said stem, a cap adapted to be screwed on said stem and having 40 a conical skirt adapted to engage with the exterior of said nozzle to prevent extrusion of the tube contents.

5. A collapsible tube having a nozzle which is 45 smooth internally and externally, a valve slideable in said nozzle and having a screw-threaded stem with a screw-threaded end projecting from said nozzle, said valve when pressed inwardly permitting extrusion of the tube contents, and when pressed outwardly preventing such extrusion, and a cap which when screwed on said 50 stem holds said valve in the latter position, and said cap itself engaging with said nozzle to prevent extrusion of the tube contents.

6. A collapsible tube having a nozzle, a valve 55 slideable in said nozzle and having a stem pro-

jecting from said nozzle, screw threads on said stem, and a cap adapted to be screwed on said stem and guiding means on the valve preventing rotation of said valve within said nozzle.

7. A collapsible tube having a nozzle, a valve 5 slideable in said nozzle and having a stem projecting from said nozzle, said valve having an axial bore and a plurality of radial bores leading to said axial bore from the interior of the tube, a cap adapted to be screwed on said stem 10 and to close said valve and said tube.

8. A collapsible tube having a nozzle, a valve 15 slideable in said nozzle and having a screw-threaded stem projecting from said nozzle, means affording a passage for extrusion of the tube contents when said valve is pressed inwardly, said valve moving outwardly to close said passage by pressure of the tube contents, and a cap which, when screwed on said stem, prevents extrusion of the tube contents.

9. A collapsible tube having a nozzle, a valve 20 member having an axial passage and being slideable in said nozzle and having a screw-threaded stem projecting from said nozzle, the inner end of said valve member being closed and having a 25 flange, said valve member being provided with at least one radial passage into said axial passage near said end whereby the tube contents may pass out of the other end of said valve member.

10. A collapsible tube having a nozzle, a valve member having an axial passage and being slideable in said nozzle and having a screw-threaded stem projecting from said nozzle, the inner end of said valve member being closed and having a 35 flange, said valve member being provided with at least one radial passage into said axial passage near said end whereby the tube contents may pass out of the other end of said valve member, said valve member being pressed outwardly 40 of said nozzle by the tube contents to interrupt extrusion of said contents when a predetermined amount of said contents has been extruded.

11. A collapsible tube having a nozzle, a valve member having an axial passage and being slideable in said nozzle and having a screw-threaded stem projecting from said nozzle, the inner end of said valve member being closed and having a flange, said valve member being provided with 45 at least one radial passage into said axial passage near said end whereby the tube contents may pass out of the other end of said valve member and a cap which, when screwed on said stem, prevents extrusion of the tube contents.
